UNITED STATES PATENT OFFICE.

CORNELIUS S. CLARK, OF NORFOLK, VIRGINIA, ASSIGNEE TO CLARK ENGINEERING CORPORATION, OF NORFOLK, VIRGINIA, A CORPORATION OF VIRGINIA.

INTERNAL-COMBUSTION ENGINE.

Application filed July 10, 1925. Serial No. 42,797.

This invention relates to internal combustion engines and proposes the provision of means to prevent the interchange of the crank case and combustion chamber fluids in the normal functioning of the internal combustion engine. In my application Ser. No. 710,882, filed May 31, 1924 means were described for segregating the non-volatile fraction of the combustible mixture which ordinarily tends to leak along the joint between the cylinder wall and piston under the urge of the compression within the cylinder, and the lubricating oil of the crank case which is commonly drawn up through the joint between the piston and cylinder into the combustion chamber upon the suction stroke of the engine. The effect of the admixture of the non-volatile fuel upon the crank case oil is to destroy the viscosity and consequently to impair the lubricating capacity of the oil. The presence of crank case oil in the combustion chamber results in fouling the spark plugs and in the rapid carbonization of the exposed surfaces of the cylinder head and piston. The purpose of the invention described in my aforesaid pending application was to overcome both of these disadvantages. The present invention has the same purpose but undertakes the accomplishment of the desired result by means which are simpler and more efficient than those disclosed in said pending application.

The present invention has for its object to prevent the presence of any non-volatile fuel in the combustion chamber as well as to provide improved means for intercepting and carrying back to the crank case the oil leaking therefrom in its passage along the joint between the cylinder and piston.

Other objects of the invention will appear as the following description of an illustrative embodiment of my invention proceeds.

In the drawings:

Figure 1 is a longitudinal view partly in section of the herein described embodiment of my invention.

Figure 2 is a longitudinal section through a portion of one of the cylinders showing the piston in lowermost position.

Figure 3 is an enlarged section of a detail showing the piston rings.

Figure 4 is a section through the injector.

Figure 5 is a section taken along the line 5-5 of Figure 1.

Figure 6 is a plan view of a portion of the suction manifold.

Referring now in detail to the several figures, the numeral 1 represents a multi-cylinder cylinder-block one of the cylinders 60 being shown in vertical section at 2 disclosing the piston 3. The piston is provided with sealing means 4 consisting of a pair of novel rings hereinafter to be described. It is to be understood, however, that the invention contemplates the use of any form of sealing means whatsoever and is not limited to the presence of but one ring or ring-groove. The cylinders are each provided with a circumferential groove 5 arranged in 65 such a position that it will be constantly overlain by that part of the piston lying between the sealing means, or the lowermost ring if several are used, and the end of the piston skirt.

The cylinder-block is provided with an integral intake and exhaust manifold, 6 being the intake passage and 7 the exhaust passage. The manifold is also formed with a chamber or reservoir 8 open at 9 to the 70 exhaust passage and having a wall 10 thereof in common with the intake passage. A conduit 11 communicates with the reservoir 8 and with the crank case 12 of the cylinder-block at 13. Intercalated in the conduit 11 is a suction producing device such as the injector 14 having a nozzle 15 through which a jet of exhaust gas from the reservoir 8 passes. The cylinder grooves 5 are in communication with the conduit 11 by means of 75 a suction manifold 16 which is connected to the injector 14 at points adjacent the nozzle 15 and in such relation to said nozzle that the velocity of the jet of exhaust gas passing therethrough produces a condition 80 of sub-pressure in the suction manifold.

In my aforementioned copending application the cylinder grooves were connected to a conduit leading into the intake manifold of the engine and dependent upon the suction of the engine for the production of the sub-atmospheric pressure within the cylinder grooves which was relied upon for freeing the joint between the piston and cylinder of surplus oil. It was found, however, impossible to prevent a certain quantity of oil from being drawn into the intake manifold and thence into the combustion chamber with the current of indrawn air. The principal effect of this was wastage of oil, al-

though a certain amount of carbonization of the walls of the combustion chamber also took place. By the substitution of the exhaust gas as a suction producing agent, the 5 induction of oil into the combustion chamber is precluded, and the velocity of the jet of oil laden exhaust gas is checked when said jet reaches the capacious chamber of the crank case, the liquid oil entrained therein 10 being dropped in the form of a spray or shower into the body of oil in the crank case, the dry exhaust gas after expansion into the crank case chamber issuing from the breather pipe (not shown) in an imperceptible 15 flow.

The reservoir 8 serves both the purpose of a hot-spot in heating the intake passage 6 and of a pressure chamber, in which the 20 impulses of the exhaust in the exhaust passage 7 are transformed into a substantially steady flow through the conduit 11. By permitting direct transfer of heat from the exhaust gases to the intake passage, the reservoir 8 accomplishes the effect of thoroughly 25 volatilizing the combustible mixture in the intake passage so that no non-volatile fraction of the liquid fuel enters the combustion chambers of the cylinders.

It will be noted from Figure 4 that the 30 injector is preferably formed with a nozzle of variable length, the object being to regulate the length of the nozzle according to requirements, depending upon the condition of the engine. If the rings are much worn 35 so that there is a tendency to pump a great deal of oil, a nozzle of greater effective length is indicated than would be the case were the sealing means in better condition.

In the illustrative embodiment of my 40 invention shown in the drawings the piston 3 has been provided with but a single groove, the same being shown in detail in Figure 3 and consisting of an upper portion 17 which is of relatively great depth, and a lower portion 45 18 of relatively shallow depth but of greater width than the upper portion. A ring 19 which is relatively thin and broad is seated in the upper portion 17 of the groove and a relatively thick ring 20 finds a seat in the lower portion of the groove. Practically 50 no play or tolerance is provided for between the inner end of the upper ring 19 and the portion of the groove in which it seats, but the usual tolerance is provided in the case 55 of the lower ring 20 so that it has a slight longitudinal translatory movement within the groove. The breadth of the upper ring gives it such degree of resiliency that when it is subject to the pressure from the combustion chamber the outer peripheral part thereof flexes downwardly maintaining a position in contact with the upper face of the 60 lower ring 20 throughout the range of movement of the latter ring, while at the same time the inner peripheral portion of the 65

upper ring remains substantially fixed with respect to the groove in which it seats. The result of this is to provide a duplex piston ring in which thermal expansion is provided for in the wide part which contacts with the wall of the cylinder, a gas-tight joint being maintained between the rear portion of the duplex ring and the bottom of the ring groove.

Using this form of ring I find that but one 75 ring to a piston gives a result eminently satisfactory when used in connection with the oil conserving device of my invention. It is, however, within the scope of the invention to use several of the duplex rings to a piston if so desired or to substitute therefor any other desired form of sealing means.

Having described my invention what I claim as new and desire to secure by Letters Patent is:—

1. In an internal combustion engine including cylinders, pistons, and a crank case, an exhaust manifold, a suction manifold communicating with the joints between said cylinders and pistons at points always within the range of travel of said pistons, a conduit leading from said exhaust manifold to said crank case, with which conduit said suction manifold communicates, and suction producing means operable by the velocity 95 of the jet of exhaust gas through said conduit for imposing a condition of sub-atmospheric pressure in said suction manifold.

2. In an internal combustion engine including cylinders, pistons, and a crank case, an exhaust manifold, a suction manifold communicating with the joints between said cylinders and pistons, a conduit including a fluid pressure reservoir of relatively large size communicating with said exhaust manifold and said crank case, with which conduit said suction manifold communicates, and suction producing means operable by the velocity of the jet of exhaust gas through said conduit for imposing a condition of sub-atmospheric pressure in said suction manifold.

3. In an internal combustion engine including cylinders, pistons, and a crank case, an exhaust manifold, a suction manifold communicating with the joints between said cylinders and pistons, at points within the range of travel of said pistons, a conduit including a fluid pressure reservoir of relatively large size communicating with said exhaust manifold and said crank case, with which conduit said suction manifold communicates, and suction producing means operable by the velocity of the jet of exhaust gas through said conduit for imposing a 115 condition of sub-atmospheric pressure in said suction manifold.

4. In an internal combustion engine, including cylinders, pistons, and a crank case, a manifold having integral intake and ex- 130

haust passages, a suction manifold communicating with the joints between said cylinders and pistons at points always within the range of travel of said pistons, a conduit communicating with said exhaust passage and having a portion thereof in heat interchanging relationship with said intake passage, with which conduit said suction manifold communicates, said conduit communicating with said crank case, and suction producing means in said conduit operable by the velocity of the jet of the exhaust gas through said conduit for imposing a condition of sub-atmospheric pressure in said suction manifold.

5. In an internal combustion engine including cylinders, pistons each having a ring adjacent the upper end thereof and a skirt, and a crank case, a manifold having integral intake and exhaust passages and a reservoir for fluid pressure communicating with said exhaust passage and functioning as a hot-spot for said intake passage, a suction manifold communicating with the joints between said cylinders and pistons at points between said rings and the ends of said skirts which are always within the range of travel of said pistons, a conduit communicating with said reservoir and with the crank case, with which conduit said suction manifold communicates, and an injector in said conduit adjacent the points of communication of said suction manifold with said conduit, said injector being operable by the velocity of the jet of exhaust gas passing through said conduit to impose a condition of sub-atmospheric pressure on said suction manifold.

6. In an internal combustion engine including cylinders, pistons each having a ring adjacent the upper end thereof and a skirt, and a crank case, a manifold having integral intake and exhaust passages and a reservoir for fluid pressure communicating with said exhaust passage and functioning as a hot-spot for said intake passage, a suction manifold communicating with the joints between said rings and the ends of said skirts at points which are always within the range of travel of said pistons, a conduit communicating with said reservoir and with the crank case, with which conduit said suction manifold communicates, and an injector in said conduit adjacent the points of communication of said suction manifold with said conduit, said injector being operable by the velocity of the jet of exhaust gas passing through said conduit to impose a condition of sub-atmospheric pressure on said suction manifold, said injector including a nozzle of variable length.

7. In an internal combustion engine, including cylinders, pistons and a crank case, said cylinders being provided with circumferential grooves communicating with the joints between said cylinders and pistons at

points within the range of travel of said pistons, an exhaust manifold, a suction manifold communicating with said grooves and with the crank case, a conduit leading from said exhaust manifold to said crank case, with which conduit said suction manifold communicates, and an injector in said conduit operable by the velocity of the jet of exhaust gas through said conduit for imposing a condition of sub-atmospheric pressure on said suction manifold and in said grooves.

8. In an internal combustion engine including cylinders, pistons each having rings adjacent the upper end thereof and a skirt, and a crank case, and manifold having integral intake and exhaust passages and a reservoir for fluid pressure communicating with said exhaust passage functioning as a hot-spot for said intake passage, said cylinders being provided with circumferential grooves communicating with the joints between said cylinders and pistons at points within the range of travel of said pistons, a suction manifold communicating with said grooves, a conduit communicating with said reservoir and with the crank case, with which conduit said suction manifold communicates and an injector in said conduit adjacent the points of communication of said suction manifold with said conduit, said injector being operable by the velocity of the jet of exhaust gas passing through said conduit to impose a condition of sub-atmospheric pressure on said suction manifold and of said grooves.

9. In an internal combustion engine including a cylinder, a piston, a crank case, a suction manifold communicating with the joint between the cylinder and piston at a point always within the range of travel of said piston, said suction manifold being in communication with said crank case, and means for utilizing the exhaust pressure for sucking oil through said manifold from between the piston and cylinder and for delivering the same to the crank case.

10. In an internal combustion engine including a cylinder, a piston having a ring adjacent the upper end thereof and a skirt, and a crank case, a suction manifold communicating with the joint between said cylinder and piston at a point between said ring and the end of said skirt which is always within the range of travel of said piston, said suction manifold communicating with the crank case, and means for utilizing the exhaust pressure for sucking oil through said manifold from between the piston and cylinder and for delivering the same to the crank case.

11. In an internal combustion engine including a cylinder, a piston having a ring adjacent the upper end thereof and a skirt, and a crank case, said piston being

formed with a circumferential groove opening into the joint between said cylinder and piston at a position between said ring and the end of said skirt which is always within the range of travel of said piston, a suction manifold communicating with said groove and with the crank case, and means for utilizing the exhaust pressure for sucking oil through said manifold from between the piston and cylinder and for delivering the same to the crank case.

12. In an internal combustion engine including a cylinder, a piston, and a crank case, said piston being formed with a cir-

cumferential groove opening into the joint between said cylinder and piston at a point always within the range of travel of said piston, said engine being provided with a passage communicating with said groove and said crank case, and means interposed in said passage and operated by the exhaust gases from the engine to cause a suction action in said passage for sucking the oil from between the piston and cylinder and for delivering the same into the crank case.

In testimony whereof I have hereunto set my hand.

CORNELIUS S. CLARK.
